BAILER BOTTOM ELEMENT

Vincent M. Vesely, Lovington, N. Mex., assignor
to C. O. Bailer Company, Inc., a corporation of
New Mexico

Application September 20, 1939, Serial No. 295,823

5 Claims. (Cl. 166—19)

The invention relates to a bailer bottom element and more particularly to a bailer attachment for use in bailing oil or water wells through the use of a pump.

The primary object of the invention is the provision of an element of this character wherein the bailer tube carries a trap and this trap is in the form of a valve having sections, these being so arranged for taking care of expansion and contraction and also to assure proper seating for the sustaining of a load in the bailing operation.

Another object of the invention is the provision of an element of this character wherein the bailer can be readily opened or closed and when opened permits dumping or unloading of the substance pumped during the drilling operation in the drilling of oil or water wells.

A further object of the invention is the provision of an element of this character wherein the trap is of novel construction and is susceptible of proper seating for the sustaining of a load and also enables the fitting thereof to different sizes of bailers.

A still further object of the invention is the provision of an element of this character which is simple in its construction, thoroughly reliable and efficient in operation, readily and easily assembled, possessed of few parts, being strong, durable, and inexpensive to manufacture and install.

With these and other objects in view, the invention consists in the features of construction, combination and arrangement of parts as will be hereinafter more fully described in detail, illustrated in the accompanying drawing, which discloses the preferred and modified forms of the embodiment of the invention and pointed out in the claims hereunto appended.

In the accompanying drawing:

Figure 1 is a vertical longitudinal sectional view through a bailer bottom element constructed in accordance with the invention.

Figure 2 is a sectional view on the line 2—2 of Figure 1 looking in the direction of the arrows.

Figure 3 is a sectional view on the line 3—3 of Figure 1 looking in the direction of the arrows.

Figure 4 is a top plan view partly in section of the modified form of trap.

Referring to the drawing in detail, particularly Figures 1 to 3 inclusive, A designates generally the bailer bottom element in its entirety and comprises a tubular body 10 constituting a bucket being of substantially uniform cross sectional internal diameter and has integral therewith at its lower end a shoe 11 the external diameter of which is slightly greater than the external diam-

eter of the said bucket body 10 to effect an external shoulder 12 with relation to said bucket body. Rotatably fitted about the body 10 is a sleeve like shutter or gate 13 having therein at diametrically opposite points discharge openings 14, these adapted to register with diametrically opposed companion discharge openings 15 in the said body 10 and when such openings are in register the bucket body can be emptied or dumped. The shutter or gate 13 is normally turned so that the openings 14 therein will be out of register with the openings 15 in the bucket body 10 for the loading thereof in the usual well known manner during bailing operation with the use of the bottom element.

The shutter or gate 13 has contact with the shoulder 12 and is fixedly and rotatably held on the said body 10 through the use of superposed jam or lock nuts 16 threaded at 17 on the body 10, these nuts being provided with wrench sockets 18 for manipulation thereof.

Arranged within the bore 19 in the shoe 11 is a sectional self-adjusting flapper valve or valves forming a trap which involves an intermediate section 20 and adjustable outer sections 21, respectively. The said sections 21 are loosely connected to intermediate section 20 to form a freely extensible and retractile flapper valve structure. The sections 20 and 21 are upwardly arched and the said intermediate section 20 is joined with a pivot arm 22 swingable on a pivot 23 fitting the said shoe, the latter being formed with a clearance 24 for the swing of the flapper or trap in a vertical direction. The intermediate section 20 is formed with elongated slots 25 arranged at the transverse median of said flapper or trap and accommodates adjustable fasteners 26 which are engaged in the outer sections 21 and in this manner the latter are susceptible of adjustment relative to the section 20 for the proper fitting and seating of the flapper or trap in the shoe.

Tapped into the shoe 11 remote from the pivot 23 or diametrically opposite the same is an adjustable seating plug or stop lug 27 engagable by the flapper or trap to maintain it in a closed position within the bore 19, in said shoe so as to have a load of substance retained in the bucket body 10 in the operation of the bailer. The body 10 is attachable to a suitable tube, not shown, usable for bailing and such tube is associated with suitable bailing tackle, not shown.

In Figure 4 of the drawing there is shown a modified form of flapper or trap which involves leaf hinge sections 28 these formed with pintle eyes or hinge pivot sleeves 29 for a pintle or hinge 55

5 pivot 30 having a terminal 31 for swingable mounting of the flapper or trap corresponding to the one involving the sections 20 and 21 herein-after set forth. Fixedly disposed crosswise of the 10 pindle or pivot 30 is a rest 32 for the sections 28 which are upwardly arched and are vertically swingable to and away from rest position on the rest 32 by the pindle or pivot 30. The last described flapper or trap is a substitute for that construction of flapper or trap first mentioned heretofore.

15 The preferred and modified forms of the flapper or trap hereinbefore set forth are designed to handle thinner substances in the bailer and to conform to the shape of the bottom element with 20 assurance of a closer seal in the closing position and a larger opening in an open position with respect to said flapper or trap, as well as allowing for expansion and contraction of such flapper in 25 the assembly thereof, as well as in the conformity with the internal bore of the shoe 11 of the bottom element.

25 The arched formation of the trap is such that when the latter is in an open position it conforms to the curvature of the cross sectional diameter of the body 10 of the bottom element.

What is claimed is:

30 1. A bailer bottom element comprising a perforated tubular body having a cylindrical shoe at one end and provided with an external annular shoulder below its perforation, a perforated sleeve-like gate movable externally about said body for registering its perforations with the perforation in the said body and resting upon said shoulder, lock nuts exteriorly about said body and operable to lock said gate in desired position, and a movable trap comprising loosely connected sections arranged within the shoe below the perforation in the tubular body.

2. A bailer bottom element comprising a tubular body having a side opening therein, means on the body for opening and closing said side opening, and a trap swingably supported in said body below the side opening and including a plurality of arched separate sections loosely adjustably connected together. 5

3. A bailer bottom element comprising a tubular body having a side opening therein, means on the body for opening and closing said side opening, 10 a trap swingably supported in said body below the side opening and including a plurality of arched separate sections loosely adjustably connected together, and a stop fixed in said body for said trap and holding the latter seated when in 15 a closed position.

4. A bailer bottom element comprising a tubular body having a side opening therein, means on the body for opening and closing said side opening, 20 a trap swingably supported in said body below the side opening and including a plurality of arched separate sections loosely adjustably connected together, and a stop fixed in said body for said trap and holding the latter seated when in a 25 closed position, and means for loosely fastening the sections of the trap together.

5. A bailer bottom element comprising a tubular body having a side opening therein, means on the body for opening and closing said side opening, 30 a trap swingably supported in said body below the side opening and including a plurality of arched separate sections loosely adjustably connected together, a stop fixed in said body for said trap and holding the latter seated when in a 35 closed position, means for loosely fastening the sections of the trap together, and a shoe formed with said body and receiving the said trap.

VINCENT M. VESELY.
